LEWIS R. COMPTON, OF EAST ORANGE, NEW JERSEY, ASSIGNOR TO THE HATFIELD RAIL-JOINT MANUFACTURING COMPANY, OF MACON, GEORGIA, A CORPORATION OF DELAWARE.

RAIL-JOINT.

1,172,009.

Specification of Letters Patent.

Patented Feb. 15, 1916.

Application filed January 31, 1914. Serial No. 815,639.

To all whom it may concern:

Be it known that I, LEWIS R. COMPTON, a citizen of the United States, and a resident of East Orange, in the county of Essex 5 and State of New Jersey, have invented certain new and useful Improvements in Rail-Joints, of which the following is a specification.

My invention relates to rail joints of the suspended type and the primary object of the invention is to produce an economical form of commercial joint so designed with the least possible amount of metal that the part of a track at the meeting ends of adjacent rails will have the same properties relative to bending resistance and elasticity as the portion of the rails intermediate their ends, or which will have properties as near those of the rail as possible with a device 15 of this character. To attain this object there is produced a coacting pair of splice bars on opposite sides of the rail, forming an element of the joint, which bars with their fastening elements, will have the material thereof so disposed that together they 20 will have a moment of inertia substantially equal to that of the rail itself and which will have the metal so disposed that the stresses to which the rails are subjected will 25 be taken and transferred from one rail to the next without straining or in any way modifying the configuration of the splice bars or without tending to twist the bars from their set position, and at the same time 30 attain these objects with the least possible cross-section of material.

Other objects of my invention are to provide a rail construction which will have a continuous uniformity of wave motion when subjected to the weight of the passing trains, which will eliminate the objectionable loosening of connecting parts and the resulting pounding at the joints, and which will maintain these conditions irrespective 40 of heat expansion or contraction, of wear, of surface disintegration of the parts, or of stretching in the holding elements. Accordingly, I provide the splice bar such as will fulfil the above conditions, or any other suitable splicing device, with such a firm engagement with the adjacent rails that stresses on the rail due to the passing trains are transferred from one rail to the next as if the rails were continuous, that is, the

wheel engaging surfaces are maintained in alignment irrespective of the position of loads on the rails and at the same time there is provided a resilient connection at the ends of the rails permitting a continuity of the vertical undulations now characterizing the 55 rails intermediate their ends.

Another object of my invention is to provide a rail joint in a device of the above indicated character, which will maintain an electric connection with the rails under all 60 conditions of service without the necessity of bonding wires.

A still further object is to so design the parts that the connections will be protected from ice, track ballast and the like without 65 the addition of any extra material for this particular purpose.

Various other objects and advantages of the invention will be in part obvious from an inspection of the accompanying drawings and in part will be more fully set forth in the following particular description of one form of mechanism embodying the invention, and the invention further consists in certain new and novel features of construction and combination of parts herein-after set forth and claimed.

Referring to the accompanying drawings:—Figure 1 is an end elevation of one form of my invention applied to the rail 75 joint and showing one of the rails in section; Fig. 2 is a side elevation of the device shown in Fig. 1 with parts broken away; Figs. 3 and 4 are views similar to Fig. 1 showing modified forms of the invention; and Fig. 5 is a section axially 80 through a spring of a form preferred for this device.

In the drawings, and referring particularly to Fig. 1, there are shown rails 1 of 95 conventional form and for the purpose of this disclosure are shown to be new A. S. C. E. standard 100 lb. rails having a moment of inertia of 43.4 calculated with reference to their neutral axis indicated by the line *a—a* of Fig. 1. An unworn car wheel 2 is shown in its normal position on the unworn rail, but as the rail and particularly the tread surface of the wheel wears away the tread surface of the rail will tend first 100 to assume the curve indicated by the dotted line *b—b* and then assume a curve substantially parallel to the original curve of the

head. Lapping adjacent ends of the rails on opposite sides thereof, are integral splicing elements comprising an inner splice bar 3 and an outer splice bar 4, each having a rail head engaging portion 5, a rail base flange engaging portion 6, in wedging engagement respectively with the rail head and bottom flange and having a connecting upstanding web 7. An integral nose 8 extends outward beyond the rail head from the portion 5 and has its upper surface 9 beveled downward from the rail head and is of a mass merely sufficient to resist thrusts, particularly outward thrusts, on the rail heads. The under surface 10 is substantially horizontal, or as near so as can be rolled, so as to fit relatively close to the spring hereinafter described.

A flange 11 depends from and underlaps the middle of the portion 6 to form an acute angle therewith, the crotch 12 of which is slightly spaced from the adjacent edge of the lower flange of the rail to permit slight movement of the bar toward the rail. This flange forms an angle of approximately 40° with the bottom of the rail and has its lower edge 13 disposed just within the mean line of stress indicated by the line $c-c$ which is taken normal to the engaging line of the under side of the rail head and the portion 5 and at the center thereof. As the rails wear away this stress is first greater on the line $c-c$ in Fig. 1 and then equalizes with line $f-f$, but the width of the web 7 is so designed that a large proportion of this line will fall within the metal of the web in all serviceable conditions of the rail.

One or more relatively short bolts 14, preferably of heat-treated alloy steel, and in this disclosure being the usual one inch bolts having shouldered ends, extend through the splice bars 3 and 4 and through apertures 15 in the web of the rail, one of said shoulders preferably being the bolt head and bearing on one of the webs 7 and the other shoulder preferably being the usual bolt nut 16.

A plate 17 is carried by the portion of two or more bolts beneath the nose 8, preferably laps the ends of the rails and engages the bolt shoulders which are on the adjacent side of the rails.

A tension member of relatively great strength, such as the coiled spring 18, is carried by one or more of the bolts 14 and has opposite ends bearing on the plate 17 and the web of the outer splice bar 4 and acts to draw, continuously, one or both of the splice bars into firm wedging engagement with the rail. The springs 18 are of sufficient tension to resist the rail disaligning effect of high speed trains passing over the joint, and as this disaligning force is frequently as much as twelve to twenty tons,

depending upon weight of traffic, etc., the coils must be constructed so as to have the maximum cross-sectional area which will conveniently fit in the space between the portion 6 and the under surface 10 of the nose 8 and may even be rectangular in section across the axis of the spring. The available spring containing space is further limited transversely of the rail, as it is desirable to confine any projecting member as close to the rail as possible so as not to interfere with the driving or withdrawing of the holding spikes 19. The coils of the spring are constructed non-circular in cross-section so as to obtain a maximum amount of material within the limited length and height of the spring space and the spring is compressed preferably until its adjacent coils touch so as to obtain the maximum tension of the spring. The coils are preferably trapezoidal in cross-section with the long parallel edges at the mandrel of the spring so that when the spring is compressed to its limit there is formed practically a solid inner core and a space permitting distortion of the spring between the outer edges of adjacent coils. With the device shown in Fig. 1 these springs each have a tension when compressed of about 2 tons so that when six springs are used the force thereof acting horizontally resolves itself into two forces, one of which is about 72 tons acting vertically upward to resist the disaligning effect on the rails of the passing trains.

As the rails themselves are designed with a definite moment of inertia to meet the requirements of stress dispositions incidental to the services required on this track, it has been desirable to make the joint of similar properties. Accordingly the joint is designed to have two characteristics of the rail, first to have a moment of inertia vertically therethrough between the meeting ends of the rail equal to that of the rail, and second to have the beam depth of the splice bars 3 and 4 along the resultant line of stress $c-c$ substantially equal to that of the rail. Aside from affording a convenient basis for designing the splice bars, this particular beam depth has been found admirably adapted for convenient installation with the standard rails. Further, should the depth of the bar be decreased from this set depth more area of section would have to be added to obtain the desired moment of inertia, and if the depth be increased the lateral stiffness would be lessened and it would be necessary to add more area to maintain lateral strength, but in addition also to the unnecessary use of metal in this instance, this would make the joint too stiff, prevent uniform wave motion of the rail and cause pounding at the joint with the resulting deterioration of the ends of the rails.

With the length and angular disposition of the depending flange described, the resultant line of stress has its greatest length for the particular beam depth and the offset in the bar around the base flange of the rail does not modify this beam action, for the offset part is reinforced by an amount of metal just necessary to take care of the increased stress produced by the leverage. 5 Considering variations from this construction, should the depending flange be shortened so that the line $c-c$ falls outside of the bar, that is, nearer the center of the rail than the tip of the flange, then there would be a 10 moment about the top of the bar which would cause a twisting or torsional stress in the bar and an increased outward stress on the bolts. If the flange be lengthened so that the stress line falls well within it, the 15 leverage will be inward but the additional metal would add to the stiffness of the joint and interrupt the uniformity of wave motion in the track under the action of passing trains. With this depth of the splice 20 bar as a constant, the moment of inertia is estimated about the horizontal neutral axis of the bar through the center of mass thereof as indicated by the line $d-d$ on Fig. 1. With the splice bars and their fastening 25 elements shown in this figure the moment of inertia of the inner bar is 21.85 and that of the outer bar 22.05 making a total of 43.9 for both bars or approximately equal to that of the rail. With this disposition of metal 30 the web 7 may be made relatively thin, the jammed coils of the spring 18 forming practically a solid extension from said web to take up transverse strains thereon. Further the bolt heads are disposed close in leaving 35 a clearance, which permits the spikes 19 to be driven with their heads inward and at the same time this disposition permits the nose 8 to be extended for lateral stiffness. This 40 relatively long nose coacts with the portion 45 6 forming in effect a channel section to aid further against outward pressure on curves without adding any material other than that necessary to take care of the vertical strains. The nose 8 extends over the springs 18 and 50 plate 17 to form a housing to protect the same in case of derailment and the inclination of the upper face 9 is such that objects falling thereon clear the bolts as they are below the tangent line $e-e$ shown in Fig. 1, 55 thus practically eliminating any shearing of the bolts. By means of this structure the spring is housed, as the web and nose of the splice bar and the plate form an inclosing structure straddling the spring and act to 60 protect the same from rock ballast, drippings from the cars or any interference with the springs. 65 Where the bolts are drawn into tight engagement with the rails and bars, and even where the heat treated alloy steel bolts are used, there is eventually produced a sufficient elongation of the bolts to lose their tight binding effect, and with the loosening of the parts pounding would take place, but the heavy interposed springs 18, by reason of 70 their powerful expansive force take up any such elongation and the bars are continually maintained in tight engagement with the rail under all conditions of the holding means. Presumably due to an electro-chemical or an abrasive action between the bars and rails, a surface disintegration takes place along the contacting surface of the rail and of the bar portions 5 and 6. But by 75 means of this construction, the splice bars 80 are capable of being pressed toward the rail web and in continuous wedging engagement with the rail head and lower rail flange as the contacting surfaces wear away by this surface corrosion, scaling or other cause. 85 This spring appears further to overcome the adhesion due to the rusting or sticking of the parts and breaks through whatever coatings, such as iron oxid, that may be formed between the rails and bars. This wedging 90 engagement causes the portion 5 to bear against the rail heads of both rails, maintaining the rails in alinement when a train load is adjacent the end of one of the rails and the open space between the spring coils 95 and the resiliency of the plate 17 both permit a giving of the rails sufficient to eliminate any feeling of rigidity when riding over the joint. 100 The outer face of the web 7 is flat and affords a broad bearing surface for the inner ends of the springs and this surface is so arranged that the strains thereon are transmitted to the rail through relatively massive parts. The plate 17 affords a broad 105 bearing for the opposite ends of the springs and this plate is of a rigidity sufficient to transmit the strains on one of the bolts to the other bolt or bolts. A further and incidental function of this structure is that 110 the bolt nuts are held from turning thereby to prevent loosening of the parts from this cause. 115 Referring to the modification shown in Fig. 3, a resilient and preferably a flexible preformed member 20, such as a compressed fabric, is disposed between the contacting surfaces of the rails and splice bars. Where the splice bar is not used as an electric conductor between rails, this member may be 120 made of some suitable electrical insulating material. 125 It has been desirable to utilize the splice bar as an electric conductor between rails to complete signal and other circuits, but an imperfect contact between the rails and bars develops after the device has been in use for a while and bonding wires are at present used to insure a continuous circuit. 130 By means of the structure herein disclosed,

the enormous pressure exerted by the springs maintains the rails and bars not only in physical, but also in electric contact and acts to overcome any break in the 5 circuit due to rusting, inertia of the parts or other causes.

A modification is disclosed in Fig. 4 to show the installation of the fastening means in connection with bars resembling the 10 standard bars and the bars are here shown with the underlapping or depending flanges 11 of Fig. 1, together with their functions above outlined, omitted and the novel binding elements are shown in connection with 15 a standard inner bar 31 and an outer bar 41, the lower portion of which resembles that of the inner bar except that the portion 6 has been slightly reduced in thickness in order to provide a foot 42 to accommodate 20 a spike hole or slot 43 beyond the plate 17, without increasing the amount of metal used.

Although I have shown only one form of mechanism embodying my invention, it is 25 obvious that various changes within the skill of the mechanic may be made therein without departing from the spirit of the invention, provided the means set forth in the following claims are employed.

30 Having thus described my invention, I claim:

1. In a rail joint, the combination with adjacent rails, of a pair of parallel strain transferring members comprising inner and 35 outer memberslapping adjacent ends of the rails on one side thereof, the outer member having a rail head engaging portion with a nose projecting therefrom adapted to resist thrusts on the rail heads, a rail 40 base flange engaging member and a connecting web, a relatively short bolt passing through one of said rails and said members, a coiled spring compressed substantially to its maximum tension carried by 45 said bolt between said nose and flange engaging portion and having opposite ends bearing on said members to maintain said inner member in engagement with the rails, said spring having the greatest possible 50 cross section whereby a spring of a strength to resist the thrusts on the rails by the passing trains may be contained in a space within in the adjacent edge of the base flange.

2. In railway track construction, the combination with a pair of rails having adjacent ends disposed in juxtaposition to form the rail joint, of a splice bar having a web lapping said juxtaposed ends, means 55 for maintaining said bar in engagement with one of said rails, said means including a plate and a tensioned member disposed between said web and said plate, said splice bar having a laterally extending rib overhanging said member, said web, rib and 60 plate forming an inclosed housing strad-

dling said tensioned member to protect the same.

3. In combination with a rail, of a splice bar in wedging engagement with the rail, a resilient member between the engaging 70 portions of said rail and bar and a compressed coiled spring with substantially contacting coils tending to move said bar toward said rail, said compressible member affording a slight movement between the 75 rail and bar in the direction which would tend to further compress the spring.

4. In a rail joint, the combination with adjacent rails, of a splice bar bridging adjacent ends of said rails, a double shouldered 80 bolt positioned through one of said rails and said bar, a coiled spring carried by said bolt and bearing on said bar and held by one of said shoulders, the adjacent coils of said spring disposed relatively close to each other 85 near the bolt and relatively far apart outward of the bolt.

5. In a rail joint, the combination with two elements thereof, of a compressed coiled spring having coils trapezoidal in cross section and held compressed between said elements, a portion of certain adjacent coils being positioned relatively close to each other and another portion being spaced relatively far apart. 95

6. In railway track construction, the combination with two rails having adjacent ends disposed in juxtaposition to form the rail joint, of a pair of splice bars lapping said juxtaposed ends on opposite sides of 100 the rails and secured thereto, each splice bar having a beam depth equal to the beam depth of one of the rails and the portions of the splice bars at the joint, each having a disposition of metal such that the sum of 105 the products of unit areas in a vertical section through said portion, multiplied by the square of the distance of said unit areas from the neutral axis of the bar, shall be equal substantially to one-half of the product of similar units of area through the rail multiplied by the square of the distance 110 of said unit areas from the neutral axis of the rail.

7. An integral rail splice bar comprising 115 a rail head engaging portion, a rail base engaging portion, a connecting web therebetween and a flange extending from said rail base engaging portion and underlapping the same, the beam depth of the bar, along the 120 resultant line of stress to which the bar is subjected, being substantially equal to the depth of the rail and the material thereof so disposed that the sums of the moments of inertia calculated about the horizontal 125 neutral axis of the bar, of a pair of coacting splice bars affixed on opposite sides of the rails at the joint, shall be substantially equal to the moment of inertia of the rail calculated about its horizontal neutral 130

axis with a resulting vertical stiffness and elasticity equal to the vertical stiffness and elasticity of the rail.

8. A splice bar for rail joints adapted to 5 lap adjacent ends of succeeding rails and to be fastened thereto, said bar having a moment of inertia vertically inclined through the bar at the portion disposed adjacent meeting ends of the rails substantially equal to one-half of the moment of 10 inertia of one of the rails, whereby a pair of splice bars disposed on opposite sides of the rails at the joint will have a moment of inertia equal to that of one of the rails 15 with a resulting stiffness and elasticity vertically equal to those of the rail.

9. A rail joint construction comprising oppositely arranged splice bars proportioned conjointly to have a vertical moment 20 of inertia substantially equal to the vertical moment of inertia of the rail, each of said splice bars being arranged with a head at its upper end in engagement with the under surface of the rail head having a substantially 25 uniform thickness below said head and being provided with a freely depending flange inwardly inclined to extend under the rail base, and of such a length as to give 30 to that of the rail and so that the flange tips will extend approximately to the mean lines of stress to which the joint is subjected.

10. A splice bar for rail joints comprising 35 a head to engage with the rail head, a vertical web, a base to engage with the top of the rail base, and a flange on said base inwardly inclined to extend under the rail and of such a length that its lower edge 40 will be positioned in a plane slightly within the plane containing the resultant lines of stress, the beam depth of the bar from the upper surface of its head to the lowest edge of the flange, being substantially equal 45 to the depth of the rail, the cross sectional area of the splice bar through the flange being such that the sum of the products of unit areas multiplied by the square of the distance of said unit areas from the neutral 50 axis of the bar of two splice bars adapted to be bolted to the rails at the joint, one on each side, shall be substantially equal to the vertical moment of inertia of one of the rails with the resultant stiffness and elasticity, said flange extending freely into the 55 space under the rail, out of contact with the rail base or with any other part.

11. In a rail construction, the combination 60 with a spring, of an integral rail splice bar, comprising a rail head engaging portion having a rib to extend beyond the rail head thereby to form an overhanging protecting ledge for the spring of greater width than the length of the spring, and having 65 a horizontal lower surface to extend over

the spring, a rail base engaging member and a connecting web therebetween adapted to form a bearing for one end of the protected spring, the space between said lower surface and that of said rail base engaging 70 member adapted to contain the spring positioned relatively close to said horizontal lower surface.

12. An integral splice bar for rail joints comprising an upstanding web, a relatively 75 massive head adapted to engage with the underside of the rail head, said head having a pointed nose extending horizontally therefrom beyond the web and beyond the rail head when in position, said nose outlined by 80 a substantially horizontal under surface and a downwardly and outwardly inclined upper surface and said nose being substantially triangular in vertical section and the outer end of the nose being capable of free movement under the action of strains on said head.

13. In a suspended rail joint construction, the combination with a pair of rails having adjacent ends positioned relatively close to 90 each other to form a joint and having base flanges, of a splice bar bridging the joint, said bar having a web portion with a vertically disposed outer face, a nose and a base flange engaging member both projecting 95 forwardly from said outer face to form a channel, a vertically disposed plate positioned within the outer edge of the adjacent flange to permit the driving of rail spikes having inwardly projecting heads at 100 the edge of the base flange, said plate forming with said channel a space substantially rectangular in vertical transverse section, a bolt in said space connecting said plate and one of said rails, a spring surrounding said 105 bolt within said space and fitting relatively close to the same, said spring having an axial cross sectional area of material substantially equal to the spaces vertically between the nose, base flange engaging member 110 and the bolt, whereby a spring of maximum tension may be disposed within this limited channel space.

14. In a rail joint construction, the combination with adjacent rails, of a splice bar 115 bridging adjacent ends of said rails, means for fastening said bar to one of said rails, and high tensioned means engaging said bar and the other of said rails and exerting a resistance of more than fifty tons to the 120 vertical rail disaligning action of the passing trains.

15. In combination, a pair of rails having adjacent ends disposed in juxtaposition to form the rail joint, a splice bar lapping said 125 juxtaposed ends, said splice bar having a beam depth substantially equal to the beam depth of one of the rails and the portion of the splice bar at the joint having a moment of inertia substantially equal to one-half of 130

the moment of inertia of one of the rails, said splice bar comprising an upstanding web, a rail head engaging portion and a rail base engaging portion extending outwardly 5 respectively from adjacent the top and bottom of said web, said rail head engaging portion including a nose outlined by a substantially horizontal under surface, a bolt extending through one of said rails and the 10 web of said splice bar, a spring surrounding said bolt and disposed between and substantially filling the space vertically between the undersurface of the nose and the top surface of the rail base engaging portion 15 of the splice bar, said spring having coils trapezoidal in cross-section and compressed with the succeeding coils substantially touching each other, said spring bearing on the bolt and on the web of the splice bar 20 and when so compressed having a depth sub-

stantially equal to the depth of the horizontal undersurface of the nose.

16. In a rail joint construction, the combination with a pair of rails having a horizontal neutral axis, of a splice-bar bridging adjacent ends of said rails and affixed thereto, said splice-bar having a depth substantially equal to the depth of the rails and having a moment of inertia calculated about its horizontal neutral axis equal substantially to one-half of the moment of inertia of one of said rails, the neutral axis of the bar being below the neutral axes of the rails. 25 30

In witness whereof I have hereunto set 35 my hand in the presence of two witnesses.

LEWIS R. COMPTON.
